ATTORNEY

UNITED STATES PATENT OFFICE.

BENJAMIN F. WILLIAMS, OF WESTWOOD, NEW JERSEY.

MATCH-LIGHTER.

1,288,782.

Specification of Letters Patent. Patented Dec. 24, 1918.

Application filed December 26, 1917. Serial No. 208,883.

To all whom it may concern:

Be it known that I, BENJAMIN F. WILLIAMS, a citizen of the United States, residing at Westwood, in the county of Bergen and State of New Jersey, have invented certain new and useful Improvements in Match-Lighters, of which the following is a specification.

This invention relates to match lighters, and particularly to a device of this character intended for the use of smokers and so constructed that the lighted match is presented for convenient application to a cigar, cigarette, or the like.

An object of my invention is to provide a device of this character which can be attached to a match box to be removably held thereon, can be fitted upon the edge of a table, or can be set in a number of other connections, and which includes a casing having an abrasive material therein against which the match will be struck, the casing acting to protect the flame and to thus assure proper lighting of the match even when in the open and when the wind is blowing.

A further object lies in constructing the parts in such a way that although the casing is closed around the flaming match, sufficient ventilation is provided to support combustion and the match is eventually disposed at an open end of the casing and at such a point that it can be conveniently and expeditiously applied to ignite a cigar, cigarette, or the like.

Yet another object lies in providing an abrasive carrying member which can be detachably placed within the casing and which can be removed and renewed as occasion may require.

With the above and other objects in view, which will be in part described and in part understood from the specification, drawings, and claims, my invention consists in certain novel features of construction and combination of parts which will be hereinafter more fully set forth.

In the drawings:

Figure 1 is a view in side elevation and with parts sectioned to illustrate the construction of the device;

Fig. 2 is a view in edge elevation of the structure disclosed in Fig. 1;

Fig. 3 is a transverse sectional view taken on the line 3—3 of Fig. 2; and,

Fig. 4 is a view in end elevation of the lighter.

The casing 1, which is here shown as being substantially square in cross section, but which might be circular, rectangular, or of other desired form, is open at one end and closed at the other as indicated at 2, the casing having a slot 3 formed along one side thereof. One of the remaining sides of the casing has the spring clip portions 4 and 5 extended therefrom and terminating in gripping edges as indicated at 6 and 7, and by slightly spreading these gripping edges 6 and 7 and fitting the spring clip portions 4 and 5 over a safety match box, the edge of the table, or over any convenient edge or object, the casing will be mounted and held in place to present the slotted opening 3 outwardly. In the present instance I have shown the casing 1 as being made up of sheet metal pieces bent and shaped to the proper form and in this disclosure the slotted opening 3 is directly opposite that side from which the spring clip portions 4 and 5 extend, these clip portions being secured to the middle of the casing and leaving an opening along that side thereof. The flange or cleat portions 8 and 9 are mounted within the casing adjacent that side from which the clip portions extend and a metal or other cleat 10 having an abrasive substance on the inner face at 11 is fitted to be held in place by these cleats 8 and 9 so that the open side of the casing is closed and the abrasive covered surface is presented opposite the slotted opening 2.

At the sides of the slotted opening 3, the metal of the casing is bent in and hooked around to provide the slide ways 12 and 13, and a sheet metal slide 14 has the edges thereof turned up and inwardly to form flanges which are received in the slide ways to mount the slide 14 within the slotted opening 3 and to be capable of movement therealong, it being understood that this slide is of substantially only half the length of the casing. The slide 14 has a match receiving opening 15 provided through that end which is adjacent the open end of the casing, and a match inserted through this opening and extended into the casing will come to bear against the abrasive surface of the plate 10. In the use of the device, the casing will be mounted upon a convenient edge or object through the medium of the spring clip portions 4 and 5, or will be held in the hand and the head end of a match is inserted through the opening 15.

of the slide 14, following which force is exerted upon the match to draw the same rather sharply toward the open end of the casing. This movement of the match will 5 scratch the head thereof along the abrasive surface of the plate 10, and as the stem of the match is fitted through the opening 15, the slide 14 will be carried with the match to close that end of the slotted opening 3 adjacent the open end of the casing while the remaining end of the slotted opening will be uncovered. As the slide 14 is brought adjacent the open end of the casing, the burning match will be presented in such a 10 way that while inclosed within the casing and protected from wind or sudden drafts, ready access will be had thereto for lighting a cigar, cigarette, or the like. If desired, a flared hood 16 can be formed or secured around the open end of the casing and thus even greater protection will be given to the burning match and the flames therefrom will be confined more intensely to the desired point. It is of course understood 15 that air must find its way into the casing to support the combustion of the match, and as the slide 14 is moved over and the inner end of the slotted opening 3 is uncovered, a direct draft passage is formed 20 through the slotted opening and through the open end of the casing, and thus sufficient air will be supplied to cause the match to ignite and burn properly.

While, in the foregoing, I have described 35 a specific embodiment of the present invention, it is to be understood that in practice, I do not limit myself to such specific details but may resort to any practical modifications falling within the scope of the invention as defined in the appended claims.

I claim:

1. As a new article of manufacture, a match lighter comprising a comparatively deep elongated casing, said casing provided 45 with an elongated slotted opening upon one side thereof, the edges of said opening being rolled to constitute tracks, a slide of less length than said opening provided with rolled edges fitting over said tracks and 50 adapted to freely slide longitudinally thereof, said slide provided with an aperture formed in the inner end thereof for receiving a match and permitting the same to be

ignited when drawn longitudinally of said casing, an igniting surface carried within 55 said casing and adapted to contact with a match extended through said aperture formed in said slide and said casing provided with an article receiving opening formed in one end thereof. 60

2. A match lighter comprising a comparatively deep elongated casing provided with a closed end and having an article receiving opening at the opposite end thereof, a shield hood comprising a plurality of flared side 65 portions extending beyond the open outer end of said casing, an igniting surface mounted snugly upon one side of said casing within the interior thereof, said casing provided with an elongated longitudinally 70 extending aperture, the match receiving slide slidably mounted within said elongated aperture and adapted to direct the match over said igniting surface, and a plurality of laterally extending substantially 75 parallel spring match box receiving jaws secured to one side of said casing.

3. A match lighter comprising a substantially elongated comparatively deep metallic 80 casing provided with an elongated longitudinally extending aperture formed upon one side thereof, the side edges of said aperture being provided with rolled portions for constituting tracks, a slide provided with rolled portions fitting around and over 85 said tracks for constituting a guide for said slide, said slide being approximately one-half the length of said casing and capable of longitudinal movement thereon, said slide provided with an aperture formed near the 90 inner end thereof, an abrasive plate secured firmly to one side of said casing at a point diametrically opposite said slide for permitting a match to move thereover for igniting the same, a shield hood formed 95 around the outer end of said casing, said casing provided with an article receiving aperture formed in said outer end adjacent said shield hood, and a match box gripping means formed upon one side of said casing. 100

In testimony whereof I affix my signature in presence of two witnesses.

BENJAMIN F. WILLIAMS.
